UNITED STATES PATENT OFFICE.

CHARLES HERBERT BURTON, OF WASHINGTON, DISTRICT OF COLUMBIA.

TOOL FOR CUTTING TONGUED BOARDING.

Application filed April 8, 1924. Serial No. 705,115.

To all whom it may concern:

Be it known that I, CHARLES H. BURTON, a citizen of the United States, residing at Washington, in the District of Columbia, have invented certain new and useful Improvements in Tools for Cutting Tongued Boarding; of which the following is a specification, reference being had therein to the accompanying drawing.

10 This invention relates to an improved tool particularly adapted for cutting tongue and grooved boarding, flooring, partitions or the like, for removing boards singly therefrom without disturbing or injuring adjoining boards and having a blade adapted to be driven in between the boards.

15 The object of the invention is to provide an improved practical form of tool of the character referred to capable of being easily operated with minimum effort or power, and that will be durable and efficient in use.

20 The invention, with other objects and advantages thereof, and the particular construction, combination and arrangement of parts comprising the same will be understood from the hereinafter contained detail description, when considered in connection with the accompanying drawings, forming part hereof, and illustrating one embodiment of the invention.

25 In the drawings:

Figure 1 is a side elevation of a tool constructed in accordance with the present invention.

30 Fig. 2 is a side elevation taken from the other side of the tool, the tool being shown in full lines with relation to a floor at the beginning of a cutting operation, and in dotted lines in position at the completion of a cutting operation.

Fig. 3 is a transverse section on the line 3—3 of Figure 2.

Fig. 4 is a top plan view, and

Fig. 5 is a detail perspective view of the tool without the blade member.

The invention comprehends a tool comprising a main body portion, a relatively thin blade on the body portion disposed longitudinally and projecting downwardly from the under side thereof, a handle extension at one end of the body portion, a forward extension at the other end of the body portion adapted to engage the work and act as a fulcrum in withdrawing the blade 2 of the tool therefrom. The enlarged part or head 6 is of a length to afford a broad bearing upon which to rock the tool on the upper surface of the floor board 7 in disengaging the blade 2 therefrom, said enlarged part or head 6 bridging the meeting faces of the adjoining boards and serving to support the tool to prevent

the handle. More particularly the invention contemplates the use of a blade pointed at one end and gradually decreasing in width longitudinally from said pointed end, and also in the use of a blade member formed as a separate part from the main body portion with means for clamping the same thereto, and means on the body portion whereby the resistance strains transmitted through the blade incident to driving the tool will be borne by the body portion and not the clamping means.

While a specific embodiment of the invention is illustrated in the drawings, it will of course be understood that changes and variations in the particular construction shown, and the embodiment of the invention in other forms, as will appeal to those skilled in the art and falling within the scope of the appended claims, may be practiced without departing from the spirit of the invention.

Referring to a detailed description of the particular embodiment of the invention illustrated in the drawings, 1 designates the main body portion of the tool in the form of a strip or bar portion shown substantially rectangular shape in cross section, and 2 is the blade of the tool disposed longitudinally of the body portion 1 and projecting downwardly from the under side thereof. The blade 2 which is relatively thin and preferably constructed of steel, has a pointed end portion 2^a, and from this pointed end 2^a gradually decreases in width lengthwise, as shown, the blade having end edges 2^b, 2^c and a lower edge 2^d extending at an acute angle to the longitudinal axis of the body portion 1. At its upper side the body portion 1 is provided with an anvil or impact part 3, said anvil part 3 being located at one end of the body portion 1 at the wider end portion of the blade 2. Extending from one end of the body portion 1 is a handle 4, and at the other end of the body portion 1 is an extension 5 that has at its outer end an enlarged part or head 6 adapted to engage the work and act as a fulcrum in withdrawing the blade 2 of the tool therefrom. The enlarged part or head 6 is of a length to afford a broad bearing upon which to rock the tool on the upper surface of the floor board 7 in disengaging the blade 2 therefrom, said enlarged part or head 6 bridging the meeting faces of the adjoining boards and serving to support the tool to prevent

twisting of the body portion 1 relatively to the blade, the enlarged part or head 6 being preferably disposed as shown to extend below the plane of the under surface of the 5 body portion 1, and also serves as a stop to limit the depth to which the blade 2 is driven into the floor. The enlarged part or head 6 has a rounded work engaging face 6^a, said enlarged part being shown cylindrical in 10 cross section, and provided with a sheath or covering 8 of felt, rubber or other suitable material to prevent the same from scratching or marring the surface of the floor boards. The body portion 1 of the tool is 15 constructed of forged steel or other suitable material, and preferably the handle 4 and the forward extension 5 are formed of the same material integral with the body portion from a continuous piece of material. In the particular embodiment of the 20 invention shown in the drawings, the blade 2 is formed as a separate part and detachably clamped to the body portion 1. The body portion 1 is provided at one side with 25 a rectangular shaped recess 9 providing a seat or socket for the upper portion of the blade 2, the upper portion of the blade being adapted to fit within the said recess are socket 9 with its top edge 2^a, and side edges 30 2^b, 2^c abutting against the walls of the recess. Means for clamping the blade within the recess 9 to the body portion is provided, said means comprising bolts 10 and nuts 11, the bolts 10 extending through apertures 35 12 in the body portion 1, and openings 13 in the blade 2. Openings 13 of the blade 2 are larger than the cross sectional size of the bolts 10 and said openings are located and shaped, as shown, so that the bolts are 40 spaced from the walls of the blade surrounding the bolt openings therein and are not subjected to the resistance strains or impacts transmitted through the blade in driving the tool, the same being taken by the body portion 1 directly through the walls of the recess 9 thereof. The nuts 11 have ratchet faced portions 11^a, and 14 is a member secured to the blade 2 and having spring tongues 14^a, 14^b, adapted to engage the 45 ratchet faces of the nuts and lock the same against turning.

In the use of the tool in removing a board from a floor, the tool, grasped by the handle 4, is held in the position illustrated in Figure 2 of the drawings with the blade 2 in alignment with the meeting line of the boards, and then driven in between the boards by blows upon the anvil part 3 by a hammer or the like. After the blade has 55 been driven down sufficiently far to sever the tongue of the board throughout the length of the blade, the blade is disengaged by pulling upwardly upon the handle 4 of the tool and rocking the tool upon the enlarged part or head 6. The tool is then 60

positioned at another place along the boards and the operation repeated.

It will be noted that by the special construction and arrangement of parts hereinbefore described, a very efficient tool is 70 afforded than can be easily operated. The tool has a handle separate and distinct from the anvil or impact receiving part by which the same can be conveniently held while driving the same. The special construction 75 having a pointed end and gradually decreasing in width as combined with the particular construction of holder or body portion provides for the entrance of the blade into the work gradually lengthwise thereof so that the same can be easily driven in between the 80 boards, and disengaged therefrom. The construction is of a strong durable nature, provision being made for employing a separate blade member detachably secured to 85 the holder, at the same time the construction is such that the resistance strains and shocks incidental to the driving of the tool is borne entirely by the body and not by the clamping 90 means.

What I claim is:

1. A tool comprising a main body portion, a blade on the body portion disposed longitudinally and projecting downwardly from the under side thereof, said blade having a cutting edge portion extending at an inclination to said body portion, the blade being adapted to gradually enter and cut the work, an anvil part on the body portion at the upper side thereof, and a handle extension 100 at one end of said body portion.

2. A tool comprising a main body portion, a blade on the body portion disposed longitudinally and projecting downwardly from the under side thereof, said blade being pointed at one end and gradually decreasing in width from said pointed end, an anvil part on the body portion located at the upper side thereof near the forward widest portion of the blade, a handle extension at one end of the body portion, and a forward extension at the other end of the body portion having a part adapted to engage the work and act as a fulcrum in withdrawing the blade therefrom.

3. A tool comprising a main body portion, a blade on the body portion disposed longitudinally and projecting downwardly from the under side thereof, an anvil part on the body portion at the upper side thereof, a handle extension at one end of said body portion, and a forward extension at the other end of the body portion having a part extending below the plane of the under face of the body portion adapted to engage the work and act as a fulcrum in withdrawing the blade from the work.

4. A tool comprising a main body portion, a blade on the body portion disposed longitudinally and projecting downwardly from

the under side thereof, an anvil part on the body portion at the upper side thereof, a handle extension at one end of the body portion and a forward extension at the other end of the body portion having an enlarged part at its outer end extending below the plane of the under face of the body portion and adapted to engage the work and act as a fulcrum in withdrawing the blade therefrom, said enlarged part having a rounded work engaging face.

5. A tool comprising a main body portion, a separate blade member disposed longitudinally and projecting downwardly from the under side thereof, the body portion having a shoulder extending longitudinally thereof against which the upper edge of the blade member abuts, means for clamping the blade to one side of the body portion, said means 10 including bolts extending laterally from the body portion at one side thereof, and through openings in the blade member, and clamping nuts to engage the bolts, the bolt opening of the blade being of a size substantially greater than the cross sectional size of the bolts and arranged so that the bolts are spaced at their side and bottom faces from the blade, an anvil part on the body portion at the upper side thereof, a handle extension 15 at one end of the body portion, and a forward extension at the other end of the body portion having a part adapted to engage the work and act as a fulcrum in withdrawing the blade therefrom.

6. A tool comprising a main body portion, 35 a separate blade member disposed longitudinally and projecting downwardly from the under side thereof, the body portion having a rectangular shaped recess in one side thereof forming a seat or socket for the 40 blade member, the blade member being adapted to fit within the said recess with its upper edge and end edges abutting against walls of the recess, means for clamping the blade within the recess to one side of the 45 body portion, said means including bolts extending laterally from the body portion at one side thereof and through openings in the blade member, and clamping nuts to engage the bolts, the bolt apertures in the 50 blade member being of a size substantially greater than the cross sectional size of the bolts and arranged so that the bolts are spaced at their side and bottom faces from the blade, an anvil part on the body portion 55 at the upper side thereof, a handle extension at one end of the body portion, and a forward extension at the other end of the body portion having a part adapted to engage the work and act as a fulcrum in withdrawing 60 the blade therefrom.

In testimony whereof I hereunto affix my signature in the presence of two witnesses.

CHARLES HERBERT BURTON.
